UNITED STATES PATENT OFFICE.

JOHN J. NEUBERT, OF ROCHESTER, NEW YORK.

ATTACHMENT FOR PANTS.

SPECIFICATION forming part of Letters Patent No. 312,884, dated February 24, 1885.

Application filed May 5, 1884. (No model.)

To all whom it may concern:

Be it known that I, JOHN J. NEUBERT, of Rochester, in the county of Monroe and State of New York, have invented a new and Improved Attachment for Pants, of which the following is a full, clear, and exact description.

The object of my invention is to provide a new and improved attachment for pants, especially to those worn by boys, whereby the strain on the suspending buttons and button-holes caused by bending, stooping, running, &c., is materially decreased.

The invention consists in the combination, with pants, of an extensible band provided with button-holes and held on the waist of the pants by elastic bands secured to the said extensible band and to the seat of the pants.

Reference is to be had to the accompanying drawings, forming part of this specification, in which similar letters of reference indicate corresponding parts in all the figures.

Figure 1 is a perspective view of a pair of boy's pants provided with my improvement. Fig. 2 is an inside view of the upper part of the back of the pants. Fig. 3 is a cross-sectional view on the line *xx*, Fig. 2.

The band A is provided with button-holes B, and a short distance from each end the band is cut diagonally, and an elastic piece, C—such as rubber band or like material—is sewed into the band—that is, to the said diagonal ends. Elastic strips or bands D are secured to the band A at their upper ends, and the button-

holes are also cut through the upper ends of the said bands D. The lower ends of the elastic bands D are secured to a transverse band, E, which is sewed to the inner surface of the upper part of the seat of the pants A. The ends of the bands A are secured to the inner surface of the pants at the sides. The buttons on the waist are passed through the button-holes B, whereby the pants are held on the waist and supported by the waist.

When the person wearing the pants bends or stoops over, the elastic bands D are stretched, and thus the strain on the buttons and the button-holes is diminished, and the buttons are not apt to tear off or the button-holes to rip.

At the same time that the band is drawn upward it is lengthened, and means must be provided for permitting such lengthening, and for that reason I have sewed the elastic pieces C into band A.

The number of bands D can be increased or decreased, as may be desired.

Having thus described my invention, I claim as new and desire to secure by Letters Patent—

The combination, with pants, of an extensible band secured to the inner side of the waist by a series of elastic strips secured to the said band and to the seat of the pants, substantially as herein shown and described.

JOHN J. NEUBERT.
